UNITED STATES PATENT OFFICE.

ERRETT B. WAGNER, OF PITTSBURGH, PENNSYLVANIA.

TOY.

1,411,944.

Specification of Letters Patent. Patented Apr. 4, 1922.

Application filed November 5, 1920. Serial No. 422,031.

To all whom it may concern:

Be it known that I, ERRETT B. WAGNER, a citizen of the United States, residing at Pittsburgh, in the county of Allegheny and State of Pennsylvania, have invented new and useful Improvements in Toys, of which the following is a specification.

My present invention has reference to a toy, in which a jointed figure having a weighted outer end is connected to a cylindrical member which is susceptible to a rocking movement and by such movement the figure is caused to assume various grotesque positions on the cylinder and also whereby the said figure influences the rocking movement of the cylinder in both directions past a dead center between the figure and cylinder.

A further object is the production of a toy in which a fanciful figure will be caused to assume grotesque positions around a roller member which is susceptible to a rocking movement, the initial position of the figure being such as to represent an attempt at rolling the figure, and the remaining positions being such as to amusingly arrange the figure in various positions around the cylinder to represent the cylinder turning the figure instead of the figure rolling the cylinder.

A further object is the production of a toy of this character which shall be of a simple construction, easily and cheaply manufactured, readily operated and one which will produce a high degree of amusement.

The foregoing, and other objects which will appear as the nature of the invention is better understood, may be accomplished by a construction, combination and operative assemblage of parts, such as is disclosed by the drawings which accompany and which form part of this application.

In the drawings:—

Figure 1 is a side elevation of a toy constructed in accordance with this invention, the full lines illustrating the initial position of the cylinder and figure, the dotted lines showing the various positions assumed by the figure when the cylinder is rocked.

Figure 2 is a sectional view approximately on the line 2—2 of Figure 1.

Figure 3 is an end elevation looking toward the line 3—3 of Figure 1.

The improvement contemplates the employment of a flat base 1 which may be constructed of light wood or any other desired

material. At its ends, the base is provided with transversely arranged depending blocks 2 that provide feet for sustaining the base a desired distance above the support for the toy.

The base, slightly beyond the center thereof has one or a number of angle openings 3 through which pass flexible elements 4 that also pass under the base 1 and between two of the blocks at what I will term the forward end of the device. The outer ends of the strands 4 are provided with rings 5, and the inner ends, which extend through the openings 3 over the base 1 are secured, in any desired or preferred manner, as at 6, to a cylindrical member 7. The member 7 is designed to represent a barrel, and is susceptible to a slight rolling or rocking movement by a pull on the flexible elements 4. 75

To the periphery of the cylinder 7, at points diametrically opposite the connecting means 6 for the flexible elements 4 there is preferably removably connected angle members 8 that are shaped to represent the arms or forelegs of the figure 9. The members 8 are pivoted, as at 10 to the body 11 of the feet. To the body there is pivoted, as at 13 members that represent the legs of the said figure. The legs have their foot portions 14 weighted.

The figure in the showing of the drawings represents a clown, but, of course, any other grotesque figure may be employed. The weighted foot portions 14 of the figure 90 normally sustain the body thereof angularly with respect to the base so that the initial position of the figure is such as to represent an attempt at rolling the cylinder 7. A pull on the flexible elements 4 through the medium of the operator grasping the rings 5 will partly roll or rock the cylinder, bringing the same toward what I will term the forward end of the device. This, of course, causes the jointed figure to be turned with the cylinder, and as soon as a dead center is reached between the figure and the cylinder, the weighted foot portions of the said figure will cause a further turning of the cylinder, the movement of the cylinder and figure being represented by the dotted lines in Figure 1 of the drawings. When the cylinder and figure have been turned to their fullest extent, the figure will assume an upside down position at the forward end of 105 the platform, and the flexible element between the apertures 3 and the cylinder 7

will be arranged at an opposite angle to the initial arrangement thereof, so that a further pull on the flexible elements will roll or rock the cylinder toward the rear of the 5 platform.

Having thus described the invention, what I claim, is:—

1. A member susceptible to a rocking motion on a surface, a jointed figure including 10 a body section and end sections, one of said end sections secured to the outer surface of the rocking member and the other end section being weighted, and the weighted end section designed to swing beyond the center 15 of the rocking member, when initial motion is imparted thereto and the figure brought to one position thereon, to further rock the said member and to halt such movement of the member when the weighted end of the 20 figure gravitates into contacting engagement with the surface on which the member is arranged.

2. In a toy, a horizontally disposed base, a member free mounted thereon and susceptible 25 to a rocking or rolling motion thereover, flexible means connected to the outer surface of the member for imparting such rocking or rolling motion thereto, a jointed figure including a body and ends, one of said ends 30 being secured to the outer surface of the member opposite the connection therewith of the flexible means, the opposite ends of the figure being weighted and normally sustained on the base, and said figure, when 35 swung upon the member when the latter is actuated to impart a rocking or rolling motion thereto, and when brought to one position with respect to said member, designed

to have its weighted ends swung beyond the center of the member to further influence the 40 rocking or rolling movement of the member and to halt such movement when the weighted ends of the figure gravitate into contact with the base, on the side thereof opposite that first occupied by the figure, and when 45 so arranged to bring the flexible operating means to a position to permit of a further rocking or rolling of the member on the base in an opposite direction.

3. In a toy, an elevated base having openings therethrough, a cylindrical member arranged on the base, flexible elements connected thereto and passing through the referred to openings in the base and designed when pulled to exert a partial rocking or 50 rolling movement to the member, and a jointed figure having an outer weighted end and an inner end which is secured on the periphery of the cylinder at a point diagrammatically opposite the connection of the flexible elements therewith, whereby, when a pull is exerted upon said elements and the cylinder is rocked or rolled, the figure will be brought to a position to bring the weighted end thereof angularly with respect to the 55 cylinder to cause a further rocking or rolling movement of the cylinder in the same direction of its travel and to further bring the flexible elements at an angle opposite to their initial arrangement to permit of a further pull thereon moving the cylinder in an 60 opposite direction.

In testimony whereof I affix my signature.

ERRETT B. WAGNER.
